HIS ATTORNEY.

UNITED STATES PATENT OFFICE.

WILLIAM E. PINCKNEY, OF PORTLAND, OREGON.

WASHING MACHINE.

Application filed July 15, 1922. Serial No. 575,201.

To all whom it may concern:

Be it known that I, WILLIAM E. PINCKNEY, a citizen of the United States, and a resident of Portland, in the county of Multnomah and State of Oregon, have invented a new and useful Washing Machine, of which the following is a specification.

This invention relates more particularly to machines for washing clothes.

10 The objects of my invention are chiefly as follows:

First. The production of a washing machine which will reverse with each revolution and in which all of the operating and 15 reversing mechanism is contained in a closed compartment which forms a lubricant reservoir for these mechanisms.

Second. The construction of a machine in which the cylinder can only be stopped 20 when its door is uppermost.

Third. The construction of an exceedingly simple and efficient clutch-throwing mechanism.

Fourth. The elimination of jumping and 25 jerking in operating the reversing movement.

Fifth. The production of an extremely noiseless machine.

Sixth. The production of a washing machine cylinder whose maximum speed will 30 be in the center of its travel and having a gradual retarding and acceleration of speed at the end and beginning of each rotation.

I accomplish these results in the manner 35 set forth in the following specification and illustrated in the accompanying drawings, in which:—

Figure 1 is an elevation of the gear box with a portion cut away in section through 40 the driving gears. Figure 2 is a section along the line 2—2 in Fig. 1. Figure 3 is a broken horizontal section showing the clutch mechanism. Figure 4 is a right hand elevation with the door of the compartment 45 containing the gear box open.

Similar numbers of reference refer to the same or similar parts throughout the several views.

Referring in detail to the drawings, I 50 have constructed my device of a wooden cylinder 20 having a removable door 21 which is held closed by the latches 22. The sides 23 of the cylinder 20 each have secured thereto a flanged hub 24 whose round- 55 ed surface 25 journals in the bearing 26

preferably riveted to the inside of the water container 27.

The water container 27 is supported by an angle iron frame whose uprights 28 are united at their upper ends by the horizontal ties 29, and at their lower ends by the horizontal ties 30. Casters 34 are provided at the lower ends of the members 38 and corner braces 35 secure the members 29 to the uprights 28.

It will be observed that the compartment for the operating mechanism between the members 28 can be reached only through the door 37. Inside of this compartment near one side of the door 37 is placed a burner 38 and a hot water coil 39 whose lower end 40 connects with the bottom of the water container 27, and whose upper end 41 opens into the water container 27 some distance up on its side.

An insulated jacket 42 and cap 43 surround the coil 39 from which fumes are carried by the pipe 44 into the atmosphere or stack as desired.

Attached to the water container 27 is a gear case within which are placed practically all of the operating mechanism of the machine. A removable cover 46 closes up the front of the gear case and prevents dust and dirt from entering and lubricant from escaping.

Journaling in the rear bearing 47 in the back 48 of the gear case is a short shaft 49 whose V-shaped end 50 projects through the side wall of the water container 27 and occupies a V-shaped slot 51 in the member 24. The upper portion 52 of the member 50 conforms with the rounded surface 25 of the member 24. Projecting into the end of the short shaft 49 is a cylinder drive clutch shaft 53 which bears at its outer end in the bushing 54 in the bracket 55 which hangs downwardly from the top 56 of the gear case.

Loosely mounted on the shaft 53 is a pinion 57 provided with a bushing 58. Clutch jaws 59 are formed on the side of the pinion 57 which is held in position on the shaft 53 by the collar 60 on the shaft 53. A pin 61 secures the shaft 53 within the member 49. Also placed on the shaft 53 is a sliding clutch member 62 whose splines 63 extend from the bushing 54 to the collar 60. A raised flange 64 extends around the clutch member 62 whose jaws 65 are adapted to

engage the jaws 59 on the pinion 57 and be rotated by same. Suspended from the top 56 are the two standards 67 supporting a rotatable shaft 68 to which are pinned the arms 69 and 70 which are urged downwardly at the ends 71 by the spring 72. A cam lobe 73 is formed on the side of the pinion 57 and comes in contact with the under side of the member 69 whenever the door 21 is uppermost. This action causes the arm 70 to rise and permit the flange 64 to pass under same—in other words, to allow the clutch jaws 65 to be moved into or out of engagement with the jaws 59.

15 In order to enable the clutch 62 to be freely moved along the shaft 53 I have formed thereon a rack consisting of the teeth 74 which are turned on the clutch member 62. Journaling in the bearing 75

20 is a shaft 76 on whose inner end is pinned a segment gear 77 which meshes with the rack teeth 74. On the outer end of the shaft 76 I have pinned a cylinder control lever 78 whose handle 79 projects above the top 80 of the machine.

25 Projecting from a boss on the inside of the back 48 is a stud 84 on which is mounted a segment gear 85 which meshes with the pinion 57. The cap 86 holds the segment gear 85 in place by means of the screw 87.

30 Projecting from the boss 88 on the front of the back 48 is a stud 89 upon which is mounted a bevel gear 90 which is held in place by the cap 91 and the screw 92. A boss 93 on the web of the gear 90 carries a crank pin 94 on which the connecting rod 95 is secured by means of the cotter 96. The connecting rod 95 is joined at its opposite end to the segment gear 85 by means of the 35 crank pin 97 on which it is secured by means of the cotter 98.

35 On the side 99 I have provided a bearing 100 in which journals the horizontal shaft 101 whose opposite end is supported by the bearing 102 mounted on the back 48. The bevel pinion 103 is pinned on the end of the shaft 101 and meshes with the gear 90. A worm wheel 104 is also pinned on the shaft 101 and drives same. A worm 40 50 meshes with the worm wheel 104 and is carried by the shaft 106 which is driven by a suitable motor.

55 On the shaft 101 are loosely placed the two miter gears 115 on whose sides are placed the clutch jaws 116 which may engage the jaws 117 of the sliding clutch member 118 joined by the spline 119 to the shaft

101. A circular rack 120 is formed around the clutch member 118.

Between the gears 115 is placed a miter gear 131 pinned to the lower end of the wringer drive shaft 132 which extends upwardly through the top 56 and bears in the boss 133 on the upper side of the top 56.

15 The lower end of the shaft 132 is supported by the bearing 132^A formed on the bracket 133^A which is secured by the screws 134^A to the back 48.

20 It is evident that in the operation of a machine equipped with my device that the clutch member 62 can only be shifted when the cam lobe 73 is uppermost, and since the position of the door 21 with relation to the lobe 73 does not change, then the cylinder 25 30 can only be stopped when the door is up.

What I claim is:

1. In a washing machine, a cylinder provided with a door on one side, and means for unclutching the cylinder with the door uppermost consisting of a shaft for driving said cylinder, a loose pinion on said shaft, a sliding clutch member on said shaft adapted to lock said pinion to said shaft, said clutch member having a flange formed on its outside and having circular gear teeth 35 cut around said clutch member, a segment gear meshing with said circular teeth, a hand lever adapted to rotate said segment gear, a pair of arms hinged to a stationary support, one of said arms engaging said flange 40 at one of its sides and the other arm engaging the side of said pinion and riding on its hub, and a cam lobe on the hub of said pinion adapted to raise said arms and permit said clutch member to be moved when the door of the cylinder is uppermost.

2. In a washing machine, a cylinder provided with a door on one side, and means for unclutching the cylinder with the door uppermost consisting of a shaft for driving said cylinder, a loose pinion on said shaft, a sliding clutch member on said shaft adapted to lock said pinion to said shaft, said clutch member having a flange formed on its outside, a pair of arms hinged to a stationary support, one of said arms engaging the clutch flange at one of its sides and the other arm engaging the side of said pinion and riding on its hub, and a cam lobe on the hub of said pinion adapted to raise said arms and permit said clutch member to be moved when the door of the cylinder is uppermost.

WILLIAM E. PINCKNEY.
